UNITED STATES PATENT OFFICE.

BENJAMAN CADMAN HANWELL GREAVES, OF SOUTH MANCHESTER, CONNECTICUT.

FLYING-MACHINE.

1,085,034.

Specification of Letters Patent.

Patented Jan. 20, 1914.

Application filed February 15, 1913. Serial No. 748,684.

To all whom it may concern:

Be it known that I, BENJAMAN C. H. GREAVES, a citizen of the United States, residing at 192 Oak street, South Manchester, 5 in the county of Hartford and State of Connecticut, have invented new and useful Improvements in Flying-Machines, of which the following is a specification.

This invention relates to flying machines, 10 and particularly to means for automatically maintaining the lateral stability thereof, the primary object of the invention being to provide means for securing an automatic adjustment of the wings of the supporting surface to right the machine when unbalanced by the excess pressure of air upon either wing, which means will serve at all times to sensitively control and maintain lateral stability.

20 A further object of the invention is to provide an automatic stabilizing mechanism which, in the event of derangement of a resisting element forming part thereof, will automatically lock and maintain the wings 25 in a normal position for safe flying.

The invention consists of the features of construction, combination and arrangement of parts hereinafter fully described and claimed, reference being had to the accompanying drawings, in which:—

Figure 1 is a front elevation of a flying machine embodying my invention. Fig. 2 is a top plan view of the machine. Fig. 3 is a side elevation thereof. Fig. 4 is a vertical longitudinal section through the body of the machine, showing the control lever and associated parts. Fig. 5 is a diagrammatic view of the wings, control lever and controlling connections.

40 Referring to the drawings, 1 designates the main frame or fuselage of a flying machine of approved type, the wings 2 and 3 of the supporting surface of which are normally disposed at a dihedral angle of a determined degree to secure inherent lateral stability. These wings, which may be of any suitable construction, are hinged or pivoted to the main frame, as shown at 4, to swing upwardly to a predetermined extent from 45 their normal positions for an automatic balancing or stabilizing action, as herein-after described. Each wing is thus mounted for movement on a horizontal longitudinal axis, and may be mounted to have any desired range of movement within safety limits.

Rising from the main frame is a triangular or pyramidal truss bracket 5 carrying pulleys 6 and 6', and secured to this bracket and to the free ends of the respective wings 60 are bracing wires or cables 7, which hold the wings from downward movement beyond their normal position, while permitting each wing to swing upwardly under excessive air pressure. Passing over the pulleys 6 and 6' 65 are shifting cords or cables 8 and 8'. The cable 8 passes over the pulley 6 and downwardly over guide pulleys 8^a and at its opposite ends extends above and below the respective wings 2 and 3 and is fastened to the 70 outer extremities thereof. The cable 8' passes over the pulley 6' and downwardly over guide pulleys 8^b and at its opposite ends extends above and below the respective wings 3 and 2 and is fastened to the outer 75 extremities thereof. It will thus be seen that if the wing 2 moves upwardly under excess air pressure, power will be communicated therefrom through the cable 8 to move the wing 3 upwardly to a like degree, while 80 if the wing 3 moves upwardly under excess air pressure power will be communicated therefrom through the cable 8' to move the wing 2 upwardly to a like degree. Each wing when forced upwardly will accordingly draw the other wing upwardly with it in such manner that both wings will at all times be disposed at an angle, thus maintaining the balance of the machine.

Pivotedly mounted upon the main frame 90 is a control lever 9 movable in a fore and aft direction on a pivot 10 and provided with a dog or pawl 11 to engage notches 12 and 13 in a fixed locking segment 14. The dog 11 is normally held retracted in such a 95 position that it will clear the notch 12 but will engage the shoulder formed by the notch 13 when the lever moves forward to the established limit. The lever is arranged in proximity to the aviator's seat, and by 100 projecting the dog 11 to engage the notch 12 the lever may be locked against motion in a stationary position to hold the wings set at a fixed angle.

The lever is normally held at its rearward limit of motion by a coiled resistance spring 15 connecting the same with an adjacent portion of the frame of the machine. The resisting pressure of this spring is made substantially equal to the air pressure upon 110 the wings when the machine is flying at a determined rate of speed. Connected with

this lever are controlling cords 16 and 17 which pass forwardly and thence outwardly and laterally over guide pulleys 18 on the frame and are connected at their outer ends 5 to the under surfaces of the wings, whereby when either wing moves upwardly to a certain degree under excess air pressure and the other wing is moved upwardly to a like degree the lever will be drawn forwardly 10 against the resistance of the spring 15 by the connections 16 and 17. By this means the excess air pressure is shed by the wing positively forced upwardly and the wings maintained at like angles, thus preventing 15 the machine from losing its poise or balance, and at the same time the degree of upward movement of the wings is restricted by the controlling device.

The lever 9 normally stands in a perpendicular position in line with the notch 12, and is maintained in such position by the action of the spring 15, which resists any upward movement of the wings 2 and 3 beyond their normal position during ordinary 25 conditions of service in the flight of the machine. If, however, excess air pressure should fall upon either wing, a pressure sufficient to force the wings upward against the resistance of the spring to such movement of the wings will limit their upward deflection to a degree just sufficient to dissipate the excess pressure, whereby an unnecessary degree of upward movement of the wings is prevented. The aviator, however, by projecting the dog 11 under engagement with the notch 12 may lock the wings in normal position against movement, whenever it is desired to throw the automatic stabilizing means out of action. If, 30 during the period of service of the automatic stabilizing mechanism the spring 15 should break at any time, the pressure of the air upon the wings 2 and 3 will move the lever forward until it is arrested by the engagement of the dog 11 with the stop shoulder 13. This will allow the wings to move upward simultaneously to a safe degree, beyond which any further movement 45 of the wings will be prevented, thus allowing

the wings to shift to dissipate the excess air 50 pressure, while preventing them from shifting beyond a safe degree. The operator, if he desires to decrease the dihedral angle of the wings to the normal, may then draw back the lever and lock it in normal position by engaging the dog 11 with the notch 12, thus holding the wings fixed at a normal 55 sustaining angle, in which event the ordinary manually controlled means commonly employed may be used to maintain 60 stability.

It will be seen that my invention provides a stabilizing mechanism which is simple of construction, as well as reliable and efficient in action, which will normally and safely 65 maintain lateral stability without the aid of the aviator, which may be thrown out of action when occasion requires, and which in the event of the derangement of the controlling spring will automatically set itself 70 to prevent the wings from having movement beyond a predetermined safe point, the advantages of which will be apparent.

I claim:

A flying machine having wings pivoted 75 for upward vertical movement upon horizontal longitudinal axes, a lever upon the car movable in a fore and aft direction, controlling cables connecting the lever with the wings, a spring acting on said lever, to resist movement thereof in one direction and coacting with the cables to resist upward movement of the wings, locking means for holding the lever against movement in normal position and locking the lever against 80 movement beyond a predetermined degree in the event of the derangement of the spring, and cables connecting the wings whereby when one wing moves upwardly 85 the other will be moved upwardly to a like 90 degree.

In testimony whereof I affix my signature in presence of two witnesses.

BENJAMAN CADMAN HANWELL GREAVES.
